C. G. HAWLEY

LOCOMOTIVE BOILER

Filed April 8, 1926

Inventor
Charles G. Hawley
by Arthur Nelson Atty.

UNITED STATES PATENT OFFICE.

CHARLES GILBERT HAWLEY, OF CLEVELAND, OHIO, ASSIGNOR TO LOCOMOTIVE FIRE-
BOX COMPANY, OF CHICAGO, ILLINOIS, A CORPORATION OF DELAWARE.

LOCOMOTIVE BOILER.

Application filed April 8, 1926. Serial No. 100,480.

This invention relates to improvements in locomotive boilers and it consists of the matters hereinafter described and more particularly pointed out in the appended claims.

5 The primary object of the invention is to provide a simple and efficient means in the side water legs of the boiler in substantially the plane of the front end of the firebox to direct a portion of the upwardly moving 10 water therein, toward the high end of the crown sheet, so that when the water level recedes to uncover said high end, the uncovered area thereon is restricted in size so that a small amount of steam escapes into 15 the firebox to warn the firemen of the actual water level irrespective of the levels indicated by the gages.

The above mentioned object of the invention, as well as others, together with the 20 many advantages thereof will more fully appear as I proceed with my specification.

In the drawing:—

Fig. 1 is a view partly in elevation and partly in section, through the firebox end 25 of a locomotive boiler embodying my invention.

Fig. 2 is a transverse vertical section through the same as taken on the line 2—2 of Fig. 1.

30 Fig. 3 is a horizontal detail sectional view as taken on the line 3—3 of Fig. 1.

Referring now in detail to that embodiment of the invention illustrated in the accompanying drawing, 1 indicates the back 35 sheet of the firebox and 2 indicates the flue sheet thereof and forming a continuation of the flue sheet is the inside throat sheet 3. The sides of the firebox are formed by the side sheets 4—4 and the top of the firebox 40 is formed by the transversely arched or curved crown sheet 5, which merges into the firebox side sheets 4—4. The side sheets and crown sheet extend between and are connected at their ends to the back sheet 1 and flue and throat sheets 2 and 3 respectively, 45 the crown sheet being inclined upwardly from the back sheet toward the flue sheet so that its highest end or head 6 is at the flue sheet end thereof.

50 The wrapper of the boiler includes a roof sheet 7, a back head 8, outer firebox sheets 9—9 and an outer throat sheet 10 together with a boiler shell 11, all in the manner well known. The front and rear water legs 12

and 13 and the side water legs 14—14 are 55 all closed at the bottom by a mud ring 15, while the bottom of the firebox is formed by the grate indicated by the dotted line 16 in Fig. 1. In the back head and back sheet respectively is formed the fuel door opening 60 17 and extending forwardly from the flue sheet 2 are the flues or tubes 18 through which the products of combustion from the firebox are drawn to the smoke box at the front end of the boiler (not shown), in the manner well known. The roof sheet and crown sheet are connected by the usual stay bolts 19, as are the side sheets 4 and 9, throat sheets 3 and 10 and back sheets 1 and 8 respectively. The construction just described 65 is typical of that type of locomotive boiler 70 now in general use and need not be described in greater detail.

In each side water leg, near its front end and toward the top thereof I provide a deflector plate 20. Each plate is preferably 75 welded to the outer side sheet and is curved upwardly and inwardly so that its free inner end overhangs the high or head end of the crown sheet and is spaced a short distance 80 above the same, said ends being equally spaced on each side the median plane of the crown sheet. Each plate 20 is provided with openings 21 through which the stay bolts 19 in the planes of said plates extend, 85 said openings being relatively large compared to the stay bolts so that there is no engagement or abrasion therebetween.

As the water in the side water legs rises under the action of the heat in the firebox, 90 said plates will direct portions of such water inwardly toward the high end of the crown sheet. When the water level falls so as to uncover the high spot or head end of the crown sheet, the water deflected by said plates will limit the uncovered dry area of 95 said head end of the crown sheet to one of such size as is safe in practice. Thus said area will under the action of the heat in the firebox become softened and will flex inwardly and will tend to pull away from the stay bolts therein which will permit steam 100 to leak into the firebox in such amounts as will be noticed by the fireman during the stoking of the firebox, who will admit feed water to the boiler to flood said dry area and rectify the boiler water level. The crown sheet 105 when completely flooded or submerged will

be safe for continued operation to complete the run but the engine is then removed from service at the first opportunity.

The deflector plates being disposed edge-wise to the plane of the forward flow or circulation of boiler water presents no interference thereto and when the crown sheet is submerged, as it will be at the proper boiler water level, said plates remain passive or inactive. However when the boiler water level falls so as to uncover the head end of the crown sheet, said plates at once become active to maintain said uncovered and dry area to one of as small dimensions as will 15 operate in the manner before described.

While in describing my invention, I have referred to certain details of mechanical construction as well as form and arrangement of the parts thereof, the same is to be taken as by way of illustration only and not by way of limitation except as may be pointed out in the appended claims.

I claim as my invention:

1. A locomotive boiler embodying therein, inner and outer stay bolted sheets defining a firebox and side water legs, and de-

flector plates positioned in said side water legs and operating at a predetermined low water level to deflect a part of the upwardly moving water in the side water legs toward 30 that area of the crown sheet which becomes uncovered and to maintain the said area to one of small dimensions.

2. A locomotive boiler embodying therein, inner and outer stay bolted sheets defining 35 a firebox and side water legs, and deflector plates positioned in said side water legs and each fixed at one end to the outer side sheets and each having its free end overhanging the crown sheet at the high end thereof, said 40 plates having openings therein through which the stay bolts extend without engagement and acting at a predetermined low water level to deflect a part of the upwardly moving water in the side water legs toward 45 that area of the crown sheet which becomes uncovered and to maintain said area to one of small dimensions.

In testimony whereof, I have hereunto set my hand, this 5th day of April, 1926.

CHARLES GILBERT HAWLEY.
